FIG. 1.

FIG. 2.

FIG. 3.

WITNESS
Emmett W. Seeman.

INVENTOR
FREDERICK W. SEEMAN.

BY

Charles E. Winer
ATTORNEY.

UNITED STATES PATENT OFFICE.

FREDERICK W. SEEMAN, OF DETROIT, MICHIGAN.

ASH-SIFTER.

1,291,190.

Specification of Letters Patent. Patented Jan. 14, 1919.

Application filed November 18, 1915. Serial No. 62,094.

To all whom it may concern:

Be it known that I, FREDERICK W. SEEMAN, a subject of the King of Great Britain, residing at Detroit, county of Wayne, State 5 of Michigan, have invented a certain new and useful Improvement in Ash-Sifters, and declare the following to be a full, clear, and exact description of the same, such as will enable others skilled in the art to which 10 it pertains to make and use the same, reference being had to the accompanying drawings, which form a part of this specification.

This invention relates to ash sifters and its primary object is an automatic ash sifter 15 having two compartments and in which the ashes are sifted into one compartment and coal and clinkers automatically delivered into the other compartment. A further object of the invention is a cheap and efficient 20 device preventing the scattering of ashes and dust, thus providing a system that may be used either in the house as well as outside thereof without inconvenience. These and other objects of the invention and several 25 novel features thereof are disclosed in the preferred form of the device shown in the accompanying drawings in which—

Figure 1 is a vertical section of an ash sifter embodying my invention showing the 30 sifter in the position assumed when delivering coal and clinkers into one compartment.

Fig. 2 is an elevation partly in section showing the sifter in position for sifting ashes into one of the compartments.

Fig. 3 is a cross section taken on line 35 $x-x$ of Fig. 2, showing the sieve and means for supporting the same.

Fig. 4 is a detail of the hinge connection showing one of the rollers upon which the 40 sieve is reciprocated.

Similar characters refer to similar parts throughout the drawing and specification.

The casing 1 is preferably formed substantially cubical in form having a hinged 45 door 2 on the top side thereof through which ashes may be placed in the sieve as herein-after described. Hinged doors 3 and 4 are provided on one side of the apparatus through which material may be removed.

The casing is divided into two compartments 50 6 and 7 by the sheet metal dividing wall 5 as indicated in Fig. 1, which wall is apertured at the upper end thereof to allow the sifter 8 to pass from one compartment 55 into the other. The sifter is box like in form, open on the upper side having the end

members 9 and 10 and a bottom 11 hinged to the frame of the sieve as more particularly seen in Fig. 4. This bottom member 11 may be formed in any approved way 60 preferably with a frame to which is secured a wire mesh of proper size for the purpose, as may be readily understood from the drawing. The side members 12 and 13 of the sifter extend beyond the end wall 10 as 65 indicated in Figs. 1 and 2, and the sieve frame 11 also extends beyond the said end wall when in closed relation as shown in Fig. 2, for the purpose hereinafter stated.

Mounted on the dividing wall 5 adjacent 70 the aperture in which the sifter rides are two rollers 14, 14 indicated more clearly in Figs. 3 and 4, which engage the bottom frame 11 and provide a roller for the sifter whereby it may easily be reciprocated. The 75 sifter is provided with an operating rod 16 having a handle 17 at the outer part of the casing, the rod extending through an aperture in the case and preferably through both the end walls 9 and 10 of the sifter as indicated in the drawings. The sifter preferably operates quite close to the top of the casing 1 and when in the position shown in Fig. 2, the hinged door 2 may be raised and ashes deposited in the sifter. By reciprocating 80 the sifter in the compartment 6 the ashes will sift through the sieve bottom 11 into the said compartment and when the ashes have been separated from the clinkers and coal the said sifter may be moved forward 85

into the compartment as indicated in Fig. 1, whereupon the hinged bottom 11 may fall as indicated by reason of the said bottom passing off from the rollers 14. As may be seen in Fig. 4 the hinged bottom 11 does not pass 90 out of engagement with the roller but the hinged point of the said bottom in passing forward of the center of the roller allows the front end of the bottom to fall gradually whereupon material in the sifter rolls 95 off from the bottom into the compartment 7. By this arrangement the ashes are delivered into one compartment and coal and such other lumpy material as is usually found in ashes is deposited in a separate 100 compartment in which they may be conveniently removed through the doors 3 and 4 provided.

To assist in the sifting of the ashes and to shake the sifter in the compartment 6 the 110 roller 14 on which the sieve bottom rides may have a knobby face as shown particu-

larly in Fig. 4, which tends to vibrate the sifter and shake the ashes out into the compartment 6. It is to be noted that the sifter has considerable movement prior to the falling of the sieve bottom as the same does not fall until the sifter has been moved very nearly completely into the compartment 7. It is also to be noted that the sieve bottom 11 is provided with a strip of sheet metal 10 at its forward end the purpose of which is to prevent ash dust from passing from compartment 6 into compartment 7 when the sifter 8 is in position as shown in Fig. 2. The sifter is preferably formed of sheet metal and riveted together in any approved manner with the proper flanges or stiffening bars at the corners but may be formed in any approved manner suitable for the purpose, the essential characteristic of which is the two compartments with the sifter adapted for movement from one compartment into the other for the purpose stated.

Having thus briefly described my invention, its utility, what I claim and desire to secure by Letters Patent of the United States is—

1. In an ash sifter, the combination of a suitable receptacle, of a partition dividing the receptacle into two compartments, a sifter reciprocal in both compartments and shorter than each compartment, said sifter having a sieve bottom longer than the

sifter, rollers mounted on the partition on which said bottom rides, the sieve frame being of such length that when the sifter is 35 moved into one compartment the bottom is held in closed relation therewith, and when moved into the other compartment falls by gravity as the hinged point of the sieve bottom passes beyond the center of rotation of 40 the rollers.

2. In an ash sifter, a receptacle, an apertured partition dividing the receptacle into two compartments, a sifter reciprocal in both compartments through the said aperture, a hinged bottom for the sifter formed of a foraminous portion equal in area to the area of the sifter and a nonforaminous portion extending beyond the end of the sifter and side members extending beyond the end 50 thereof, the said extension of the bottom and side walls in conjunction with said end of the sifter closing the aperture to one compartment when the sifter is drawn thereinto, and rollers mounted on the upper edge of 55 the partition on which the said hinged bottom rides, allowing the sieve bottom to fall by gravity on movement of the sifter into the other compartment to discharge the contents thereof.

In testimony whereof, I sign this specification.

FREDERICK W. SEEMAN.
